Collingswood, N. J.

Application July 18, 1946, Serial No. 131,670

Term of patent 3½ years

(Cl. D19—2)

To all whom it may concern:

Be it known that I, Frederick T. Paden, a citizen of the United States, residing at Collingswood, in the county of Camden and State of New Jersey, have invented a new, original, and ornamental Design for a Casket Handle Bracket or Similar Article, of which the following is a specification, reference being had to the accompanying drawing, forming a part thereof.

Figure 1 is a front elevational view of a casket handle bracket or similar article, showing my new design.

Figure 2 is a rear elevational view of the same.

Figure 3 is a side elevational view of the same.

Figure 4 is a top plan view of the same.

Figure 5 is a bottom plan view of the same.

I claim:
The ornamental design for a casket handle bracket or similar article, as shown.

FREDERICK T. PADEN.
